GLAZING AND POLISHING MACHINE

Forrest R. Whitcomb, Worcester, Mass.

Application February 26, 1947, Serial No. 731,145

18 Claims. (Cl. 51—84)

1

This invention relates to a machine for glazing or polishing surfaces on metal products and particularly including knife blades. The polishing operation is commonly termed "mirror-finishing."

It is the general object of my invention to provide an improved machine for such purposes, by the use of which a very fine glazed or mirror surface may be obtained.

To the accomplishment of this general object, I provide novel hydraulic actuating and control mechanism for my improved machine, including means by which the pressure on the work may be controlled and varied and by which the pressure on the work may be automatically and entirely removed during reversal of work travel. I also provide novel means for balancing the weight of the reciprocated parts, and means for utilizing differential oil flow to increase or decrease the pressure of the polishing rolls against the work.

My invention further relates to arrangements and combinations of parts which will be herein-after described and more particularly pointed out in the appended claims.

A preferred form of the invention is shown in the drawings, in which

Fig. 1 is an end view of my improved glazing and polishing machine;

Fig. 2 is a partial rear elevation, looking in the direction of the arrow 2 in Fig. 1;

Fig. 3 is a diagrammatic view of the hydraulic actuating and control mechanism;

Fig. 4 is a sectional elevation of a control valve which provides differential oil flow to the roll-advancing cylinder;

Fig. 5 is a sectional elevation of a balancing valve to be described;

Fig. 6 is a sectional plan view of a reversing valve which controls the movements of the polishing rolls toward or away from each other;

Figs. 7 and 8 are rear elevations of parts of this valve, looking in the direction of the arrows 7 and 8 in Fig. 6; and

Fig. 9 is a front elevation of a disc member, looking in the direction of the arrow a in Fig. 6.

Referring to Fig. 1, my improved glazing and polishing machine comprises a pair of polishing rolls R which are preferably abrasive-covered cloth rolls. Each roll R is rotated by a belt drive 10 from a motor M mounted on a pivoted platform 12. The pivoting of the platform allows the roll R to be moved toward and away from the work during the operation of the machine, while the weight of the motor M holds the belt drive at uniform tension in all roll positions.

2

The rolls R are rotatably mounted on bearing arms 14 and 15 secured to rock shafts 16 and 17. These arms are moved toward and away from each other by a double-acting hydraulic cylinder 5 C and its associated piston. The limit of approach of the rolls to each other is determined by an adjusting screw 18 associated with the arm 14 and a telescoping tubular abutment 19 secured to an arm 20 fixed to the shaft 17.

The work W is suspended from a traverse bar 22 mounted for horizontal movement between pairs of guide-rolls 23 and 24 on a work head 25. The work head is vertically reciprocated on fixed posts or columns 27 and is actuated by a piston 15 28 (Fig. 3) in a lifting cylinder C'.

The work W is traversed horizontally by a piston 30 in a hydraulic cylinder C2. The cylinder C2 receives oil under pressure at one end or the other under the control of a master valve V', 20 which in turn is controlled by a reversing valve V2 shiftable by dogs or fingers 32 on the traverse bar 22. Oil for the operation of the machine is supplied by a hydraulic pump P driven by a motor M' (Fig. 3). The flow of oil to the lifting cylinder C' is controlled by a master valve V3 (Fig. 3), 25 which in turn is controlled by a reversing valve V4 having arms 33 and 34 engaged by fingers 35 on an upright rod 36 associated with the vertically reciprocated work head.

As the rod 36 moves upward with the work, the intermediate finger 35 will engage the arm 33 at the upper limit of travel and reverse the valve V4, which in turn reverses the master valve V3 and shifts the supply of oil to the opposite end 30 of the lifting cylinder C'. As the rod 36 moves downward with the work, the upper finger 35 will engage the arm 34 and shift the valve V4 in the opposite direction. The lower finger 35 is used to limit over-run of the work head in an upward direction for inspection or reloading.

The details of construction and control of the valve V4 to permit over-run, and certain associated devices for starting and stopping the machine form the subject matter of a companion application, Serial No. 731,146, filed February 26, 45 1947.

The throttle valve V5 in the main supply line from the pump is associated with the over-run control and may be opened and closed by the 50 same hand lever which shifts the arms 33 and 34 axially relative to the fingers 35 to effect over-run.

Provision is made, as shown in said companion application, for limiting the opening of the 55 throttle valve V5 which controls the speed of

operation of the lifting and traversing mechanism. Independent regulation of the speed of operation of the work-supporting traverse bar 22 in the work head 25 is secured by provision of a manually-operated regulating valve V6 in the supply line for the master valve V2. If no traverse is desired, the valve V6 is closed.

A pressure cylinder C3 acts to absorb hydraulic shock at the moment of reversal of the work head, which head is of substantial weight.

A differential valve V8 controls the flow of liquid to the left-hand end of the cylinder C which swings the rolls R toward and away from the work. A reversing valve V9 is associated with the differential valve V8 and is shifted at the upper and lower limits of work travel by dogs 40 and 41, adjustably secured on an upright bar 42 secured to the work head 25 and vertically reciprocated therewith.

The upper dog 40 engages shifting pins 44 (Fig. 1) on the inner face of a segmental plate 45 associated with the valve V8, and the lower dog 41 similarly engages pins 46 on the outer face of the disc 45. The dogs and pins are so arranged that either dog, after reversing the valve V9, may freely continue its travel in the same direction and without damage to the valve-shifting mechanism.

The pressure of the rolls R on the work W may be varied by a cam plate 50 (Fig. 2) associated with the movable bar 42 and vertically reciprocated therewith. The cam plate 50 engages one arm of a bell crank 52 mounted on a fixed pivot 53. The outer end of the other arm of the bell crank engages the head 54 (Fig. 4) of a plunger 55 forming a part of the differential valve V8.

A balancing valve V10 (Figs. 3 and 5) is provided to supply increased back pressure below the piston 28 to offset the weight of the work head and associated parts during downward movement thereof.

Differential valve

The valve V8 which controls the operation of the cylinder C in moving the rolls R toward and away from the work is of special construction, the details of which are clearly shown in Fig. 4.

The valve V8 is connected to the reversing valve V9 by a pipe 60 and is connected through a pipe 61 to the left-hand end of the roll-positioning cylinder C. The opposite end of the cylinder C is directly connected to the reversing valve V9 through a pipe 62.

Assuming that the rolls R are to be advanced toward the work, oil under pressure flows through the pipe 60 (Fig. 4) to a passage 65, passing over a check valve 66. The oil then flows through a passage 67 to a recess 68 and past an open valve 70 to a chamber 71, from which the oil flows through a passage 72 to the pipe 61 leading to the left-hand end of the chamber C. As the arms 14 and 15 are substantially on dead center in vertical position, only extremely light oil pressure is needed to advance the rolls to engage the work.

As soon as such engagement takes place, however, the resistance to further advance movement of the rolls causes the pressure to increase in the various passages of the differential valve V8. This increased pressure acts against a piston 73 and depresses the piston against the resistance of a spring 74. As the piston 73 is thus moved downward, the valve 70, previously held raised by the piston rod 75, is moved downward by gravity and a light spring 76 and closes the direct connection between the recess 68 and the chamber 71. The

Oil from the supply pipe 60 thereafter travels from the recess 68 through a by-pass 80 to a passage 81 which is connected at one end to the chamber 71 and at the opposite end to a passage 82 which opens into an exhaust connection 83. Flow of oil from the recess 68 to the by-pass 80 is controlled by a needle valve 85 which has a head 86 for manual adjustment.

The connection between the passage 81 and the exhaust passage 82 is controlled by the plunger 55 previously described. This plunger has a beveled lower end, as shown in Fig. 4, and is yieldingly raised by a spring 90 against the pressure of the bell crank 52 (Fig. 2).

In the operation of the cylinder C to advance the rolls R toward each other, there is an initial and substantially free flow of oil past the valve 70 until the rolls engage the work, whereupon the pressure rises, due to resistance to further roll advance. This increased pressure closes the valve 70, and there is then restricted flow past the needle valve 85 to the passage 81. A part of the oil flowing into the passage 81 is delivered through the chamber 71 and pipe 61 to the cylinder C, and a part of the oil escapes past the plunger 55 to the exhaust pipe 83.

The ratio of oil delivery between the pipes 61 and 83 is determined by the position of the beveled plunger 55, which in turn is determined by the cam plate 50. As the cam plate moves upward and downward with the work, the position of the plunger 55 may be varied as desired to correspond with the varying contour of the work or to any variation in the work area engaged at a given point by the rolls R.

As the work head 25 approaches its limit of travel in either direction, the reversing valve V9 is actuated by a dog 40 or 41 to reverse the connections to the valve V8 and the cylinder C through the pipe 60 and 62, so that the pipe 62 then becomes the supply pipe and the pipe 61 becomes the exhaust pipe.

Liquid exhausted from the left-hand end of the cylinder C then flows upward through the pipe 61 (Fig. 4) and lifts the check valve 66, thus providing a direct connection of substantial capacity to the pipe 60, which is now the exhaust pipe. The valve 70 also opens to provide additional exhaust capacity. Consequently the movement of the rolls R away from the work is very rapidly performed.

Balancing valve

The construction of the valve V10 which balances the work head 25 is shown in Fig. 5. Oil from the master valve V3 is delivered to the valve V10 through a pipe 92, and the valve is connected to the lower end of the lifting cylinder C' through a pipe 93. The valve V10 comprises an upwardly opening valve member 95 which is normally seated and closed by a relatively heavy spring 96. A downwardly opening valve member 97 is mounted in an axial passage 98 in the valve member 95 and is normally closed by a light spring 99.

When the pipes 92 and 93 act collectively to supply oil to the lower end of the cylinder C' for raising the piston 28 (Fig. 3) and the work head 25, the oil flows freely downward through the axial passage 98 in the valve member 95 and around the lightly loaded valve member 97, which readily yields to downward pressure.

When the pipes 92 and 93 act collectively to exhaust the lower end of the cylinder C' during downward movement of the work head 25 and piston 28, the valve 97 will be closed by the oil pressure 76 sure and will then act as a check valve. The

outer valve member 95 must then be lifted against the relatively heavy spring 96, thus maintaining a relatively heavy back pressure in the lower end of the cylinder C' during downward travel of the work head. This arrangement takes care of the substantial difference in load during upward and downward movements of the heavy work head 25.

Reversing valve

The reversing valve V9 is of special construction and is so designed that movement of the segmental plate 45 in either direction from normal position by a dog 40 or 41 will reverse the oil connections to the valve V8 and to the cylinder C and will move the rolls R apart at reversal of work travel in either direction. As soon as travel thereafter begins in the reverse direction by operation of the valve V4, the same dog 40 or 41 will return the valve V9 to normal position and will thus immediately restore the hydraulic connections to the operative condition necessary for applying pressure to the rolls.

The details of construction of the valve V9 are clearly shown in Figs. 6 to 9. The valve V9 (Fig. 6) comprises a base 100, a cap 101 and a disc member 102. The base 100 (Fig. 7) has a central cylindrical recess 105 with a rear axial port 106 connecting through an exhaust pipe 107 to the storage tank for the pump P. The pipe 60 from the valve V8 is connected to a recess 108 in the base 100 and has a port 110 opening therefrom into the central recess 105. The pipe 62 from the right-hand end of the roll-swinging cylinder C is similarly connected through a recess 111 to a port 112.

The cap 101 (Figs. 6 and 8) has a central cylindrical recess or pressure chamber 115 and has a hub 116 for a stud 117, to the outer end of which the segmental plate 45 is secured. At its inner end, the stud 117 has a head 118 provided with a cross rib 119. A supply pipe 120 (Fig. 3) from the pump P is connected through a passage 121 to the cylindrical recess or chamber 115 which is always under pressure.

The disc member 102 (Fig. 9) has ports 130, 131 and 132 extending therethrough and also has an exhaust recess 135 provided with arms 136, 137 and 138. Shallow recesses 140 are provided in the face of the disc member 102 to reduce friction, and the pressure in these areas is relieved by bleed openings 141.

The disc member 102 (Fig. 6) has a groove 144 in its outer surface to receive the cross rib 119 previously described, so that the disc member 102 and segmental plate 45 will rotate together.

The parts are shown in Fig. 6 in position to supply pressure to the pipe 60 and valve V8 to press the rolls R against the work. In this position, the port 130 in the disc member 102 is aligned with the port 110 in the base 100, so that oil under pressure supplied through the pipe 120 (Fig. 8) to the pressure chamber 115 will be delivered to the pipe 60 connecting to the differential valve V8. The valve V8 then supplies oil through the pipe 61 to the left-hand end of the cylinder C, and the rolls R are thus advanced and pressed against the work.

At the same time the pipe 62 from the right-hand end of the cylinder C is connected through the recess 111 and port 112 to the arm 136 of the exhaust recess 135 and thus through the exhaust passage 106 to the exhaust pipe 107. This is the normal or running position of the parts.

If the plate 45 and the valve member 102 are displaced in either direction by a dog 40 or 41,

one of the ports 131 or 132 will connect the pressure chamber 115 through the port 112 in the base to the pipe 62, thus applying pressure in the right-hand end of the cylinder C to separate the rolls R. At the same time one of the arms 137 or 138 of the exhaust recess 135 will be aligned with the port 130, thus connecting the left-hand end of the cylinder C through the differential valve V8 and pipe 60 to exhaust.

The valve V9 thus provides hydraulic connections to press the rolls R against the work when the valve is in normal or mid position, and provides connections to quickly separate the rolls and release the pressure on the work whenever the segmental disc 45 is displaced in either direction at the end of work travel by a dog 40 or 41. A spring-pressed ball 158 (Fig. 6) holds the valve V9 yieldingly in mid-position if at any time it is not held by oil pressure and friction. Valve V9 may be turned manually 180° to render the valve inoperative when automatic pressure relief is not required.

Operation

Having described the details of construction of my improved machine, the operation thereof is as follows:

The work W is suspended from the traverse rod 22 and receives limited and relatively slow traversing movements, mainly for distributing the wear on the polishing rolls. These traversing movements are effected by the cylinder C2 under control of the master valve V' which in turn is controlled by the reversing valve V2 operated by dogs 32 on the traverse bar 22. This traversing operation is continuous so long as the pump P is in operation and the throttle valve V5 is open. The speed of the traversing motion is controlled by the regulating valve V6, which may also be used to stop all traverse.

The work head 25 which carries the work-supporting traverse rod 22 is vertically reciprocated by the cylinder C' which alternately receives oil under pressure at its upper and lower ends by operation of the master valve V3. During downward movement, the weight of the work head and associated reciprocating parts is balanced by increased back pressure in the valve V10.

The master valve V3 is controlled by the reversing valve V4, which is alternately shifted angularly by fingers 35 on the rod 36 which is vertically reciprocated with the work head. The upper and lower fingers 35 control normal travel of the work head and the lower finger 35 limits upward over-run. This over-run is accomplished by manually shifting the arms 33 and 34 of the valve V4 axially. Further movement of the same shifting lever (not shown) closes the throttle valve V5 to stop the machine at any desired point.

The cylinder C3 acts as a shock-absorber and prevents hydraulic knock as the work head is reversed at the end of its travel.

The rolls R are moved toward and away from the work by the cylinder C under the control of the differential valve V8 and the reversing valve V9. The valve V9, as previously described, normally maintains pressure in the pipe 60 to move the rolls toward each other and to apply pressure to the work. The valve V9 is shifted at the upper and lower ends of normal travel by the dogs 40 and 41, and when so shifted applies pressure through the pipe 62 to separate the rolls R.

The pins 44 and 46 on the segmental plate 45 are so arranged that the same dog which shifts the valve out of normal position will immediately

return the valve to normal position as soon as the return movement of the work head and dog begins. Consequently the rolls R are moved away from the work at both extreme limits of travel and are returned to again engage the work as soon as reverse travel begins. This prevents engagement of the rolls with the work during the time of reversal when the work is substantially motionless. Otherwise lines or shadows would be produced in the finished surfaces.

The pressure of the rolls against the work during the travel of the work is controlled and may be varied by the cam plate 50 which moves vertically with the work head and which varies the position of the plunger 55 in the valve V8 through the medium of the bell crank 52. Movement of the plunger 55 varies the flow to the exhaust pipe 83 and reversely varies the flow to the pipe 61 connected to the roll-operating cylinder C.

The cam plate 50 may be made with any desired taper or with a contoured surface, so that the pressure may be varied to correspond with the work area in contact with the rolls at any given point in the vertical reciprocation of the work. This variable control of the roll pressure against the work is extremely important and enables me to produce glazed and mirror surfaces of very unusual quality.

Having thus described my invention and the advantages thereof, I do not wish to be limited to the details herein disclosed, otherwise than as set forth in the claims, but what I claim is:

1. In a glazing and polishing machine, a work head, means to reciprocate said head, a pair of coacting work-engaging rolls, means to press said rolls against the work, and means to vary the pressure of the rolls against the work in predetermined relation to the work travel during the finishing operation thereon and while the rolls remain in engagement with the work.

2. In a glazing and polishing machine, a work head, means to reciprocate said head, a pair of coacting work-engaging rolls, means to press said rolls against the work, and means to relieve the roll pressure as the work head approaches each end of its locus of reciprocation and during reversal thereof and while the rolls remain in engaging relation with the work.

3. In a glazing and polishing machine, a work head, means to reciprocate said head, a pair of coacting work-engaging rolls, means to press said rolls against the work, and means to relieve the roll pressure as the work head approaches each end of its locus of reciprocation and during reversal thereof and while the rolls remain in engaging relation with the work and to restore the roll pressure as the reverse movement begins.

4. In a glazing and polishing machine, a work head, means to reciprocate said head, a pair of coacting work-engaging rolls, means to advance said rolls to engage the work with very light pressure, and means to thereafter increase the roll pressure on the work during the finishing operation thereon and while the rolls remain in engagement with the work.

5. In a glazing and polishing machine, a work head, means to reciprocate said head, a pair of coacting work-engaging rolls, means to advance said rolls to engage the work with very light pressure, and means to increase the roll pressure as the work is engaged by the rolls and to vary the roll pressure during the work travel and in predetermined relation thereto.

6. In a glazing and polishing machine, a work

head, means to reciprocate said head, a pair of coacting work-engaging rolls, means to advance said rolls to engage the work with very light pressure, means to increase the roll pressure as the work is engaged by the rolls, and means to entirely relieve the roll pressure at each end of each reciprocating movement of the work during the finishing operation thereof and while the rolls remain in engaging relation with the work.

7. In a glazing and polishing machine, a pair of work-engaging rolls, hydraulic means to press said rolls against the work and including a hydraulic by-pass connection, manual means to control the flow through said by-pass connection, and automatic means to vary the roll pressure by bleeding said by-pass connection.

8. In a glazing and polishing machine, a pair of work-engaging rolls, hydraulic means to press said rolls against the work and including a hydraulic by-pass connection, and automatic means to vary the roll pressure by bleeding said by-pass connection and in predetermined relation to the work travel.

9. In a glazing and polishing machine, a pair of work-engaging rolls, hydraulic means to press said rolls against the work, a supply of liquid under pressure for said hydraulic means, and a differential device effective to reduce the operating pressure of said liquid.

10. In a glazing and polishing machine, a pair of work-engaging rolls, hydraulic means to press said rolls against the work, a supply of liquid under pressure for said hydraulic means, a differential device effective to reduce the operating pressure of said liquid, and automatic means to vary the setting of said differential device.

11. In a glazing and polishing machine, a pair of work-engaging rolls, hydraulic means to press said rolls against the work, a supply of liquid under pressure for said hydraulic means, a differential device effective to reduce the operating pressure of said liquid, and manual means to vary the flow of liquid to said differential device.

12. In a grinding and polishing machine, a reversing valve having supply and exhaust connections and two operating connections, and a valve member movably mounted in said valve and provided with ports and with an exhaust recess, said ports and said exhaust recess being so disposed that displacement of said valve from normal position in either direction will reverse the relation of said operating connections to said supply and exhaust connections.

13. In a grinding and polishing machine having a work head and hydraulic means including a cylinder and piston to vertically reciprocate said head, in combination, means to balance the weight of the reciprocated parts on the down stroke comprising a back-pressure valve in the pipe which is connected to the end of the cylinder which is exhausted on said down stroke, said valve having a valve member opening under relatively light pressure toward said cylinder and a second valve member opening under relatively heavy pressure away from said cylinder.

14. In a glazing and polishing machine, a work head, means to reciprocate said head, a pair of coacting work-engaging rolls, means to press said rolls against the work, means to relieve the roll pressure as the work head approaches each end of its locus of reciprocation and to restore the roll pressure as the reverse movement begins, and means to vary the pressure of the rolls against the work in predetermined relation to the work

travel and during the finishing operation on the work.

15. In a glazing and polishing machine, a work head, means to reciprocate said head, a pair of coacting work-engaging rolls, means to press said rolls against the work, cam means reciprocated with the work head and controlling the roll pressure on the work in predetermined relation to the work travel, and means to relieve the roll pressure as the work head approaches each end of its locus of reciprocation and to restore the roll pressure as the reverse movement begins.

16. In a glazing and polishing machine, a work head, means to reciprocate said head, a pair of coacting work-engaging rolls, hydraulic means to press said rolls against the work, differential means to control the flow of the hydraulic liquid, and means to relieve the roll pressure as the work head approaches each end of its locus of reciprocation and to restore the roll pressure as the reverse movement begins.

17. A glazing and polishing machine as set forth in claim 16, in which the differential control means includes a valve member which is variably positioned in predetermined relation to the reciprocation of the work.

18. In a glazing and polishing machine, a valve mechanism comprising a feeding connection to admit operating liquid to said machine, means

5 to maintain said feeding connection initially open against relatively light operating pressure, a restricted by-pass connection, means responsive to heavier operating pressure and effective to close said feeding connection as the operating pressure increases, a device to bleed said by-pass connection to reduce the effective pressure of the operating fluid delivered to said machine while said initially-open feeding connection remains closed, and automatic means to selectively change the setting of the bleeding device to provide differing reduced pressures.
